(57) **CLAIM**

The ornamental design for a cell phone protector case, as shown and described.

DESCRIPTION

FIG. 1 is a front perspective view of the cell phone protector case, showing our new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

The dot-dash broken lines represent the bounds of the claimed design. The dash-dash broken lines depict environmental subject matter that forms no part of the claimed design. The broken lines and regions bounded by broken lines form no part of the claimed design.
